CLAIM

We claim the ornamental design for an interface portion of a battery pack, as shown and described.

DESCRIPTION

FIG. 1 is a rear perspective view of an interface portion of a battery pack, such as a battery pack for a power tool, an outdoor tool or other battery-powered device according to a first embodiment.

FIG. 2 is a front perspective view of the portion of the battery pack shown in FIG. 1.

FIG. 3 is a rear view of the portion of the battery pack shown in FIG. 1.

FIG. 4 is one side view of the portion of the battery pack shown in FIG. 1.

FIG. 5 is another side view of the portion of the battery pack shown in FIG. 1.

FIG. 6 is a top view of the portion of the battery pack shown in FIG. 1.

FIG. 7 is a rear perspective view of an interface portion of a battery pack, such as a battery pack for a power tool, an outdoor tool or other battery-powered device according to a second embodiment.

FIG. 8 is a front perspective view of the portion of the battery pack shown in FIG. 7.

FIG. 9 is a rear view of the portion of the battery pack shown in FIG. 7.

FIG. 10 is one side view of the portion of the battery pack shown in FIG. 7.

FIG. 11 is another side view of the portion of the battery pack shown in FIG. 7; and,

FIG. 12 is a top view of the portion of the battery pack shown in FIG. 7.
